UNITED STATES PATENT OFFICE.

FRANK W. DRISH, OF SULLIVAN, ILLINOIS, ASSIGNOR OF ONE-HALF TO JOHN R. POGUE, OF SULLIVAN, ILLINOIS.

LACE-ROD BRACKET.

1,035,329.

Specification of Letters Patent. Patented Aug. 13, 1912.

Application filed February 25, 1911. Serial No. 610,780.

To all whom it may concern:

Be it known that I, FRANK W. DRISH, residing at Sullivan, in the county of Moultrie, in the State of Illinois, have invented a new and Improved Lace-Rod Bracket, of which the following is a specification.

My invention has relation to curtain and shade fixtures and has for its object to provide a simple, neat and inexpensive bracket for supporting the curtain rod or pole, that can be readily applied to the ordinary window shade or blind hanger in such manner that all the nailing and marring of the window casing is done away with.

My invention comprises generally a metal bracket formed of a single piece of metal bent to shape for supporting one or more lace rods, and into a combined clamp and hook member slidable up on the ordinary blind hanger and connectible therewith without disturbing the position of the hanger already fastened to its operative position.

In its more subordinate features my invention consists of a lace rod bracket embodying the peculiar construction and arrangement of parts all of which will be hereafter fully explained, specifically pointed out in the appended claims, and illustrated in the accompanying drawings in which:

Figure 1, is a perspective view that illustrates my invention as in use. Fig. 2, is a perspective view of one of my lace rod brackets and shows the manner in which it is applied to the ordinary forms of shade hangers. Fig. 3, is a view of the pole holder applied to the hanger. Fig. 4, is a view of a slightly modified form of my invention.

My improved curtain pole holder or bracket is bent up to form the desired shape from a single piece of metal, preferably stout spring wire and the same comprises the vertical or back member 1 the lower end of which is bent back upon itself to form a reinforced bearing portion 10, thence bent into a U shaped loop that is bent down in a plane parallel with the portion 10 to form a spring clamp 11, the formed member 11^a of

which merges with a downwardly extended portion 12 bent back upon itself to form a second bearing portion 10^a, which with the portions 10 and the U shaped clamp 11, forms a combined supporting and clamping foot for the bracket, for slipping over and interlocking with the outwardly extended flat arm 2^a of the common type of shade hanger bracket 2, which as shown, has a bulged portion surrounding the roller pin 55 pindle receiving aperture and an apertured right angle portion for seating against the casing. From the bearing 10^a the wire strand is extended forwardly and upwardly as at 13 and thence outwardly to form the front end of the bracket and thence it is bent to form a U shaped hanger 14 for supporting the pole α and from which the wire extends horizontally inwardly and terminates in a hook 15 for interlocking with the hook 16 in the upper end of the back member 1.

In Fig. 4 the shape of the bracket differs from the form shown in Figs. 1 to 3, in that the wire strand extends horizontally forwardly from the bottom of the bearing portion 10^a to form a hanger 17 for holding a second pole α .

From the foregoing taken in connection with the accompanying drawing the construction, the manner and use of my invention will be readily apparent. Among the advantages it should be mentioned that the same can be easily slipped upon and clamped to the ordinary flat arm 2^a of the bracket shade hanger and thus save all nailing and marring of the window casing. It can be quickly adjusted and since the bearing members 10—10^a extend below the U shaped clamp loop 11 a solid footing for the bracket is provided, and by reason of the said clamp loop 11 fitting between the bulged part and the angle member of the bracket 2 the said bracket 1 is also held from laterally slipping upon the said flat arm 2^a of the bracket 2.

Having thus described my invention what I claim is:

A curtain pole holder formed of a single

strand of wire, bent to form a vertical back member, a foot portion that includes a hook shaped pendent clamp adapted for slipping over and clamping the extended flat arm of 5 a shade hanger bracket, the front end being bent to form a seat for the curtain pole, the upper end of the vertical back member and the rear end of the curtain pole seat member being secured together.

FRANK W. DRISH.
